PIPE OR SIMILAR DEVICE

Richard J. Finn, 1870 Winding Brook Way,
Scotch Plains, N.J. 07076

Filed Dec. 2, 1971, Ser. No. 204,399

Term of patent 14 years

Int. Cl. D27—02

U.S. Cl. D85—8 A

FIG. 1

FIG. 2

FIG. 3

FIG. 1 is a perspective view of a pipe or similar device showing my new design;

FIG. 2 is a top plan view with surface shading partially removed for ease of illustration; and

FIG. 3 is a side elevational view also with partial surface shading.

The plugged end not shown has no aperture.

I claim:

The ornamental design for a pipe or similar device, substantially as shown and described.
